(57) CLAIM

The ornamental design for a toilet cleaning tool, as shown and described.

DESCRIPTION

FIG. 1 is a perspective view of a toilet cleaning tool embodying our design;

FIG. 2 is a side view of the toilet cleaning tool shown in FIG. 1;

FIG. 3 is a top view of the toilet cleaning tool shown in FIG. 1;

FIG. 4 is a bottom view of the toilet cleaning tool shown in FIG. 1;

FIG. 5 is a front view of the toilet cleaning tool in FIG. 1; and,

FIG. 6 is a rear view of the toilet cleaning tool shown in FIG. 1.

The portions of the tool shown in broken lines are for illustrative purposes only and form no part of the claimed design.
